GARDEN IMPLEMENT PICK HEAD OR SIMILAR ARTICLE

George M. Philpott, Sr., 220 E. Grand Ave.,
South San Francisco, Calif. 94080

Filed Dec. 6, 1973, Ser. No. 422,361

Term of patent 14 years

Int. Cl. D8—01

U.S. CL. D8—11

FIG. 2

FIG. 3

FIG. 1

FIG. 5

FIG. 4

FIG. 6

FIG. 1 is a perspective view of a garden implement pick head or similar article embracing my new design; FIG. 2 is a front elevation thereof;

FIG. 3 is a rear elevation of the article shown in FIG. 1;

FIG. 4 is one side elevational view thereof wherein the opposite side elevational view is an identical mirror image thereof;

FIG. 5 is a bottom plan view of the article shown in FIGS. 1 to 4, inclusive; and

FIG. 6 is a top plan view thereof.

I claim:

The ornamental design for a garden implement pick head or similar article, as shown and described.
